ALBERT BROADMEYER, OF HARRISBURG, PENNSYLVANIA, ASSIGNOR TO THE W. O. HICKOK MANUFACTURING CO., OF HARRISBURG, PENNSYLVANIA, A CORPORATION OF PENNSYLVANIA.

FEED-INTERRUPTING MECHANISM.

1,183,628.

Specification of Letters Patent.

Patented May 16, 1916.

Original application filed May 20, 1915, Serial No. 29,926. Divided and this application filed August 5, 1915. Serial No. 43,782.

To all whom it may concern:

Be it known that I, ALBERT BROADMEYER, a subject of the Emperor of Germany, and a resident of Harrisburg, in the county of 5 Danphin and State of Pennsylvania, have invented certain new and useful Improvements in Feed-Interrupting Mechanism, of which the following is a specification.

My present invention relates generally to 10 paper feeding machines of that nature described and shown in my application Number 29,926, filed May 20, 1915, and is, more particularly, an improved mechanism for interrupting the operation of the feeding parts 15 at certain times during use of the machine, this application being a division of my application Serial Number 29,926, just mentioned.

The primary object of my present invention is to provide simple, strong, and durable means for automatically interrupting the feed of the paper when more than a single sheet is moved from the stack at one time, and to do this by breaking the driving 20 connections through the positive action of means directly controlled by the paper being fed.

In the accompanying drawings illustrating my invention and forming a part of this specification: Figure 1 is a plan view of my improved machine. Fig. 2 is a side elevation thereof. Fig. 3 is a detail side elevation of a portion of the machine, particularly illustrating in detail certain of the parts 30 thereof to which this application directly relates. Fig. 4 is a detail vertical section taken substantially on line 4--4 of Fig. 3. Fig. 5 is a view partly in side elevation and partly broken away and in section showing 35 the clutch at one end of the shaft of the feed tape roller shown in Figs. 1 and 2. Fig. 6 is a vertical section taken substantially on line 6--6 of Fig. 5. Fig. 7 is an elevation of part of the clutch shown in Fig. 5 with 40 the parts in unclutched position, and Fig. 8 is a vertical section through the clutch, taken 45 on line 8--8 of Fig. 5.

Referring now to Figs. 1 and 2 it will be seen that at the rear of the feeding machine 50 as shown, is arranged a frame in which the feed table is vertically adjustably disposed,

this frame consisting of a base 50 from which a pair of standards 51 rise at each side, the upper ends of these standards supporting upper side frames 52, rigidly connected and spaced apart by transverse tie rods 53 and 54 as best seen in Figs. 1 and 2.

By referring to Fig. 2 it will be noted that the upper side frames 52 have journals for the upper ends 55 of screw bars 56, disposed between the standards 51 at each side of the feed table frame, the upper extremities of which screw bars are provided with fixed bevel gears 57 in mesh with similarly fixed bevel gears 58 of a transverse shaft 59 journaled at its ends through the upper portions of the upper side frames 52, it being also seen in Fig. 2 that one projecting end of the shaft 59 at the right hand side of the machine and looking forward, as will be seen 60 by reference to Fig. 1, is provided with a ratchet wheel 60 rigidly secured thereto and having at one side a clutch connected with a crank 63.

At each side of the feed table frame thus 65 formed is arranged a longitudinally extending bracket 64 having end yokes 65 (see Fig. 2) engageable with the standards 51 in sliding relation, and having a central threaded bearing 66 through which the respective 70 screw bar 56 extends, whereby upon rotation of the feed bars 56, the supporting brackets 64 will be raised and lowered, dependent upon the direction of such rotation.

The paper stack 76 as seen in Figs. 1 and 85 2, is held on the table 69 between guides 75 and 77.

Being thus located in proper position between the guides 75 and 77, the paper stack is moved forwardly against the upper end of 90 spaced rigid upright guide strips 81 as plainly seen by reference to Fig. 2, this position shown in said figure, being the normal position of the stack ready for operation, although it is to be understood that the 95 guides 75 and 77 are laterally adjustable with respect to the feed table in order to accommodate a desired width of paper. With the stack thus disposed in proper position, and elevated through the use of the 100 hand crank 63 of the controlling shaft 59, the sheets are removed one at a time and fed

forwardly by the action of a suction cylinder 82 journaled transversely above the forward edge of the feed table and immediately above the upper end of the forward spaced 5 upright paper guide strips 81 before mentioned, the relative arrangement of this suction cylinder 82 being readily seen by reference to Figs. 1 and 2.

In order to effect automatic vertical adjustment of the feed table 69 during feed of the paper, automatic means are provided adjacent thereto actuated by a crank and pitman 105 from an end disk 107 of the suction cylinder 82, as seen in Fig. 1, the details 10 of which automatic means are included in a separate application filed August 5, 1915, and serially numbered 43783. Around a pulley 108 connected to shaft 59 by a clutch 110 is extended the rear end of a belt 114, 15 the forward end of which belt, as plainly seen in Fig. 1, is extended around one end portion of the suction cylinder 82, so that when the pulley 108 is clutched the rotation of the suction cylinder 82 is communicated 20 to the shaft 59, rotating the same to similarly rotate the screw bars 56 and lower the table 69 when its paper stack has become exhausted.

From Fig. 5 and also from Fig. 2, it will 30 be noted that one of the bearings 66 of the adjacent side bracket 64 is provided with an extended bearing or tubular piece 115 loosely through which extends a vertical rod 116 having an adjustable set collar 117 secured thereon below the said side bracket, and with which the extended portion 115 just mentioned comes into engagement when the table is lowered through the action of the belt 114, thus causing lowering movement 35 of the rod 116, the upper end of which is secured to a flexible connection 118 passing over a pulley 119 supported upon the adjacent upper side frame 52 and connected at its forward end to a clutch operating member 40 for disengaging a clutch in the driving connections to the suction cylinder 82, as hereinafter described, when the table 69 has thus been lowered.

Referring again to Fig. 1, it will be noted 45 that the reduced end portion of the suction cylinder 82 is provided with a pair of gears 168 and 169 in respective connection with separate gears 170 and 171 of the shaft 172 of a wooden roller 167. The sheets of paper 50 delivered by the action of the continuously rotating suction cylinder 82 upon tapes 166, the rear ends of which pass around the wooden roller 167, and the forward ends of which pass around a roller 179, as seen in 55 Fig. 1, and carried forwardly by said tapes in their movement between side paper guides 180 and 181 parallel with the side frame bars 182 and 183, are delivered between superposed rollers 184 at the rear of the ruling

machine, the rear portion of the frame 185 of which is clearly shown in Figs. 1 and 2, the rollers 184 receiving the paper, having interchanging gears 186 and 187 at their outer ends, the latter of which is driven through a suitable gear train, from a suitable source of power, and one gear of which train is indicated at 188 in Fig. 2. The gear 187 is also provided with a sprocket wheel 189 and from this sprocket wheel a sprocket chain 190 extends longitudinally along and 65 outside of the frame side bar 183 as will be clearly seen by reference to Fig. 1, with its rear end around a sprocket wheel 191 loosely disposed upon one projecting end of the shaft 172 of the wooden roller 167 before 70 mentioned. This sprocket wheel 191 is connected to the shaft 172 of the wooden roller 167 by means of an automatic clutch to be now described, as particularly shown in 75 Figs. 5 to 8 inclusive.

Referring now to Fig. 5 it will be seen that the sprocket wheel 191 is rigidly attached by machine bolts 192 to the outer side of an annular disk 193 also loose upon the shaft 172, this disk carrying a pair of spring 80 controlled pawls 194 normally in engagement with the teeth of a ratchet wheel 195 secured upon the shaft 172 as clearly seen in Fig. 6, pawls 194 having laterally and inwardly projecting pins 196 adapted for 85 engagement by the annular beveled face 197 of a clutch controlling member 198 longitudinally shiftable with respect to the shaft 172 and having at its inner end a cam shoulder 199 normally disposed within a conformable recess 200 at the outer end of a sleeve 201 disposed on the shaft 172 and held against rotation by means of pins 202 rigid therewith and entering recesses in the adjacent bearings 174 of the shaft 172 as 90 plainly seen in Fig. 5, the relatively engaging cam shoulder 199 and recess 200 being plainly seen in Fig. 7. Thus rotative movement of the clutch controlling member 198 in either direction serves to shift the same 95 longitudinally of the shaft 172 toward the ratchet wheel 195, the result being that its conical face 197 engages the pin 196 of the pawls 194 so as to shift the pawls on their pivots away from, and out of engagement 100 with, the ratchet wheel 195 before mentioned.

To this end the clutch controlling member 198 has an upright rigid arm 203 to which the forward end of the flexible connection 118 is secured, the rear end of which connection is secured to the vertically shiftable rod 116 as before described. To the upright arm 203 is also connected the rear end of a connecting rod 204 extending forwardly along the machine and connected at its forward end to a cam disk 205, as will be plainly seen by reference to Figs. 1, 2,

and 3. Referring now particularly to Fig. 3, it will be noted that the connection of the forward end of the actuating rod 204 is above the fulcrum 206 of the cam disk 205 upon the outer face of the frame side bar 183, and that to this cam disk 205 the upper end of a retractile spring 207 is connected at a point forwardly of the fulcrum 206, the lower end of said spring being anchored in the lower portion of a vertically adjustable bracket 208 as best seen in Fig. 4, which is held in adjusted position in connection with the frame side bar 183 by a set screw 209. The upper portion of the cam disk 205 is provided with a forwardly presented shoulder 210 engaged by the lower end of a threaded pin 211 adjustably mounted through the forward end of an arm 212, the rear end of which is securely fastened to a cross shaft 213 above and forwardly beyond the wooden roller 167 before mentioned, so that the cam disk 205 is normally held in its inactive position as best seen in Fig. 3.

The shaft 213 just mentioned extends transversely above the series of tapes 166, its ends projecting through upright bearings 214 attached to the side frame bars 183 as best seen by reference to Figs. 1, 2, and 3, and is provided with forwardly and rearwardly projecting arms 215 and 216 respectively, the latter arm being loosely connected to the shaft 213 to swing freely in a vertical direction thereon, and having at its rear bifurcated end a roller 217 bearing upon the wooden roller 167 as shown in Fig. 1 and acting to press the paper downwardly into engagement with the tapes 166 and thus promote a steady uniform movement of the paper so fed.

The forwardly projecting arm 215 is rigidly connected at its rear end to the said shaft 213, and is provided at its forward end with a roller 218 as plainly seen in Figs. 1 and 3, which roller bears downwardly upon a companion roller 219 mounted upon a lower transverse shaft 220 (see Fig. 1), extending between the side frame bars 182 and 183 below the upper run of the tape 166, this latter shaft 220 being provided at one side with a sprocket wheel 221 connected by a sprocket chain 222 (see Fig. 3) with a sprocket wheel 223 secured to one end of the wooden roller 167 as seen in Fig. 1, the shaft 220 being thus driven from the wooden roller 167. The roller 219 of the shaft 220 projects upwardly to substantially the level of the upper run of the tapes 166 and the arm 215 being rigid with the shaft 213 upward movement of arm 215 under the pressure of the sheet of paper passing beneath the roller 218 serves to raise arm 215 and thus oscillate the shaft 213 to a limited extent which is permitted by adjustment of the vertical pins 211 before

mentioned and controlling the cam plate 205. When, however, two sheets are fed at the same time upon the tapes 166, the increased thickness of the material so fed causes upward movement of the arm 215, oscillating the shaft 213 to such an extent that the vertical movement of the pin 211, in consideration of the fact that the arm 212 is of greatly increased length with respect to the arm 215, elevates the pin 211 out of contact with the shoulder 210 of the cam plate 205, which cam plate is thereupon rocked upon its fulcrum 206 by the action of the spring 207 so as to move rod 204 forwardly to oscillate the clutch controlling member 198 with which rod 204 is connected as before described thus releasing the clutch through the action of the parts thereof as previously described.

Forwardly of the cam piece 205 is a transverse shaft 224 journaled through the side frame bars 182 and 183, and provided at one side adjacent to the cam plate 205 and beneath its forward extension 225, with a rearwardly projecting crank 226 having a roller 227 which, upon oscillatory movement of shaft 224, is adapted to engage upwardly beneath the forward extension 225 of the cam plate 205 and elevate said cam plate to its normal locked position as shown in Fig. 3, after automatic release thereof due to the attempted passage of two or more sheets at the same time along the tapes 166, the relatively opposite end of shaft 224 having a handle 228 adjacent the forward end of this machine and therefore adjacent the operator's station indicated by the arrow A in Fig. 1.

Thus from the foregoing description of the construction and operation of the several parts of this machine, it is believed that its operation as a whole may be readily understood. It is to be noted, however, that in addition to the automatic release of the clutch shown in Figs. 5 to 8 inclusive by the passage of two or more sheets beneath the roller 218, the operator may release these parts by the operation of a handle 274 carried by the end of the shaft 213 opposite to that to which the arm 212 is connected, as best seen in Fig. 1. It is also to be understood that the table 69 may be lowered through the action of belt 114 from the suction cylinder 82. As before described, when the table has been lowered until it engages the set collar 117, thereby lowering rod 116, the clutch is withdrawn by rearward oscillating movement of the clutch operating member 198; thus disrupting the driving connections. When a new supply of paper sheets has been furnished, the table is then elevated to the proper position as best seen by reference to Fig. 2, by the hand crank 63. It will be understood that a machine so

constructed will be light in weight, practical and efficient in its operation, and strong and durable in use, and that the feeding parts may be controlled through the adjustment of the driving connections best shown in Fig. 2 from the ruling machine, so as to accurately and minutely adjust and time the feeding operation in accordance with the movement of the operating parts of the ruling machine itself, sheets being fed either at desirably spaced intervals, or in a practically continuous manner without danger of two or more sheets arriving at the ruling machine at the same time, and with the attention of but a single operator.

It is further to be understood that while I have shown and described my improvements particularly in connection with a ruling machine, they may be adapted with equal facility in connection with printing machines, embossing machines, paper box making machines, sizing apparatus, and in fact any machinery to which it is desired to feed sheets of paper in substantially the manner set forth, and each of the foregoing references to a ruling machine is therefore to be taken as merely representative of the class of machinery to which my invention is adapted for application.

30 I claim:—

1. In a paper sheet feeding machine, a series of feed tapes along which the sheets are fed, a roller over which said tapes extend, driving connections for said tapes including a clutch on the shaft of said tape roller, a spring actuated member for releasing the clutch to arrest movement of the tapes, and means engaging and normally holding said member in inoperative position, including a roller operating adjacent the feed tapes and acted upon by the passage of more than one sheet at a time, to release the said clutch releasing member.

2. In a paper sheet feeding machine, a series of feed tapes, a roller over which said tapes extend, a roller beneath which the sheets are fed along the tapes, driving connections for said tapes including a clutch on the shaft of said tape roller, normally inoperative means for releasing the clutch to arrest movement of the feeding tapes, connections between the said roller and the said clutch releasing means to normally hold the latter inoperative, said connections being movable by the vertical movement of the said roller to release said clutch releasing means when more than one sheet at a time is fed under the roller.

3. In a paper sheet feeding machine, a series of feed tapes along which the sheets are fed, driving connections for the said tapes including a clutch, a spring actuated clutch releasing member connected to the clutch, an elongated controlling arm nor-

mally engaging and holding the said clutch releasing member against movement, a roller disposed above the tapes and beneath which the sheets pass, and connections between the said roller and the said arm whereby to raise the latter and permit movement of the clutch releasing member when the roller is moved vertically by the passage of more than a single sheet at a time upon the tapes.

4. In a paper sheet feeding machine, a series of feed tapes along which the sheets are fed, driving connections for the said tapes including a clutch, an oscillatory shaft journaled above the tapes, a relatively short arm adjustably secured to the said shaft and provided at its outer end with a roller beneath which the sheets are fed upon the tapes, a relatively long arm also secured to this said shaft at one end and provided at its opposite end with a latch pin, a clutch releasing member having connection with the clutch and having a shoulder normally engaged by the said latch pin, and a spring connected to the said clutch releasing member for moving the same when the latch pin is raised by vertical movement of the said roller.

5. In a paper sheet feeding machine, a series of feed tapes upon which the sheets are fed, driving connections for the tapes including a clutch, a pivoted clutch releasing member having connection with the clutch and having an upright shoulder and an extension at one side of its pivot, an actuating spring connected with the said extension, a shaft journaled above the tapes and provided with a relatively short arm and a relatively long arm, a stop pin adjustably mounted through the outer end of the long arm and engaging the shoulder of the said clutch releasing member to normally hold the same inactive, and a roller carried by the relatively short arm and beneath which the sheets pass in their travel upon the said tapes.

6. In a paper sheet feeding machine, a series of feed tapes, driving connections for the tapes including a clutch, a spring actuated clutch releasing member connected to the clutch and provided with an extension, connections normally holding the said clutch releasing member inactive, and including a roller disposed above the tapes and beneath which the sheets carried by the said tapes are forced to pass whereby to release the clutch releasing member when more than one sheet is fed at a time, and a resetting device for the said clutch releasing member including a shaft having a handle and a crank disposed below the extension of the said clutch releasing member to elevate the same to normal position after release thereof.

7. In a paper sheet feeding machine, the combination with the feeding parts, of driving connections therefor including a clutch, and means operating with the feeding parts for releasing the clutch when two or more sheets are fed at the same time, said means including a spring actuated member connected to the clutch, and locking means having adjustable engagement with said member for normally holding said member inactive and including a movable element beneath which the paper is fed.

ALBERT BROADMEYER.
